PIANO CHORD PLAYER

Daniel McFarlan Moore, East Orange, N. J.

Application April 5, 1934, Serial No. 719,184

1 Claim. (Cl. 84—443)

This invention relates to the pianochord which is a small and simple device or contrivance which rests on the top of a desired number of piano keys. It is preferably about as wide as the black keys are long. A simple form consists primarily of four (4) chordbars, each one of which when depressed produces a musical chord. An acceptable accompaniment can be played for most songs and hymns by the use of less than a half dozen chords. Therefore, by selecting for one simple form of my pianochord the four (4) chords most used in compositions, like songs and hymns, very acceptable accompaniments can be played for most of them by simply pressing, in proper sequence, one (1) chordbar at a time, and thus obviate the necessity of the somewhat formidable task of training the fingers. The striking of a dischord becomes almost an impossibility if one (1) chordbar is used at a time.

Instead of picking out a tune with one finger that strikes one piano key at a time, the one finger with my pianochord can pick out a tune by striking a chord of three or more piano keys at a time instead of one piano key at a time.

A typical attempt to mechanically play the piano is exemplified in the well known and formerly widely used pianola, which is a large and very expensive instrument involving among its many parts foot treadles for producing pneumatic pressures and also a perforated paper roll for each tune.

The principal object of my invention is to provide the simplest possible method and device for obtaining desired harmonies from a piano.

My invention will best be understood in connection with the following drawings:

Figure 1 is a perspective view of a simple form of the pianochord in place on a piano keyboard.

Figure 2 is a plan view of a simple form of pianochord.

Figure 3 is a front elevation of the pianochord shown in plan in Figure 2.

Figure 4 is an end elevation of the pianochord shown in plan in Figure 2.

Figure 5 is a plan view of a pianochord in which several modifications have been introduced.

Figure 6 is a side elevation of the pianochord shown in Figure 5.

Figure 7 is an end elevation of the pianochord shown in Figure 5.

Figure 8 is a plan view of a portion of a modified chordbar.

Figure 9 is an elevation of the chordbar shown in Figure 8.

The gamut of the pianochord shown in Figure 1

extends from the piano key E up to and including E b. Obviously, the pianochord can be moved to any of the octaves that are above or below. This is facilitated by the placing of the letter C, which designates the key C of the keyboard, as shown, on the side of the pianochord in Figure 3.

It has four (4) chordbars, each producing one complete chord by its single downward movement due to the pressure of one or more fingers. Accompaniments suitable for an indefinite number of tunes can be played by properly using these four fundamental musical chords. However, any single piano chord instrument containing a selected group of chords of a definite key and designed for a specific location on the keyboard can not always produce a satisfactory accompaniment for all tunes. Musical science indicates that there are thirty-six (36) chords, that can, if desired, be applied to the pianochord, namely; twelve major triads, twelve minor triads, and twelve major triads with the addition of the seventh. Maximum usefulness, however, to the public will probably be obtained by the selection for a pianochord of the half dozen or so chords which can be made to produce the most acceptable accompaniments for the largest numbers of hymns and songs. The manufacturing cost in quantities of a simple pianochord is only a matter of cents.

Fundamentally, there are seven (7) chords possible for each musical key of which there are seventeen (17) to the octave. Also, each chord of three piano keys can be played or arranged in three positions. Elementally, to play the pianochord successfully consists in anticipating which chord, that is available, will momentarily best suit the progressing tune. Any individual endowed with a natural musical ability to think or hum or sing or whistle a specific tune can play an accompaniment on the pianochord. Also, anyone even without musical ability can produce harmonies and melodies by simply pressing down the pianochord bars. A chordbar can be depressed with only one finger or with eight, if desired. The technique of pianochord playing has many niceties and variations.

These four wooden chordbars are held in their proper places by a wooden rectangular frame one inch high and which is numbered 5 on Figures 2, 3, and 4. Its sides rest on the opposite ends of all of the black keys beneath them. In Figure 2 the four bars are numbered 1, 2, 3, and 4. The overall length of this frame is 8 $\frac{1}{4}$ inches. Its width is 2 $\frac{3}{8}$ inches. Each chordbar is 8 $\frac{1}{8}$ inches long, $\frac{1}{2}$ inch wide, and $\frac{5}{8}$ inches high. These

four chordbars fit loosely within the frame. They cannot fall out of the frame when the pianochord is removed from the piano because of the small cross battens marked 6 and 5 6', prime, and 7 and 7', prime, in Figures 2, 3, and 4.

and time, so that if it is carefully followed the interpretation will be uniform. For example, a modified form of my pianochord music incorporates the element of time and "Jesus, Lover of My Soul" I write as follows:

5

15 The battens 7 and 7', prime, are located loosely between the sides of the unused black keys C# and F# and prevent lateral movement of the frame. The inner ends of 7 and 7', prime, touch the vertical portion of the piano which is at the end of all of the keys, and thus definiteness and stability is obtained for the pianochord. The chordbars have a maximum up and down movement of about $\frac{1}{8}$ of an inch and from the bottom side of each extend 3 or 4 striking teeth on the bottoms of which felt is glued. The striking teeth are $\frac{3}{8}$ inch in section, and for the white keys $\frac{3}{4}$ inches long, and for the black $\frac{5}{8}$ inches. Their size, material, or construction, can be greatly varied.

30 The chordbar marked 1 in Figure 2 shows that it has 3 teeth, and depresses the piano keys G, Bb and Eb, and is the sub-dominant chord of Eb.

The chordbar marked 2 plays, F, Bb and D, and is the tonic seventh chord of Bb.

35 The chordbar marked 3 plays the keys F, A, C, and is the dominant chord of F seventh.

The chordbar marked 4 plays G, Bb and C, and is the super tonic seventh chord of C seventh.

40 To aid in proving the usefulness of my invention I have produced a useful accompaniment with the assistance of the model of pianochord I have just described, for about four score each of well known popular and sacred tunes. Most 45 of them only required the use of three chordbars and some only two. Players who are naturally musical soon learn to know when to manipulate each of these four chordbars, somewhat similar to the technique acquired by a typist or pianist. A trained pianist naturally attempts to play all of the chordbars, one at a time, with the most convenient finger of the right hand, or, play a melody or air on the piano keys above the pianochord with the right hand and with the 50 left hand play the pianochord in unison. However, for the benefit of pianochord beginners, and those not naturally musical, I have evolved a very simple method of assisting them by writing down which bar to use next, as a tune they know, progresses.

60 For example, the so called music for the pianochord for—Jesus, Lover of My Soul, can be written as follows:

65 24—33—23—1—2—3—2 R
24—12—2 R
24—33—23—1—2—3—2

70 The figures refer to the chordbars that should be pressed and released. The subfigures refer to the number of times that a chordbar needs to be pressed before using the next chordbar indicated. R means repeat.

75 Such nomenclature is very useful to individuals playing an air that they know. But, properly written music should include a record of tone

15 The figures (or numerals) indicate the individual members of the chordbars, and show which one should next be pressed and released. For each circle beneath a chordbar number, the chordbar should be pressed once. The larger the circle, the longer the interval of time before a 20 chordbar is released. R means repeat.

For the practical application of this system of music to most popular tunes when their accompaniment is produced by the use of a pianochord, four sizes of circles are usually sufficient. For 25 example—

- can correspond to a whole note.
- can correspond to a half note.
- can correspond to a quarter note.
- can correspond to an eighth note.

30

Longer or shorter time intervals can be used, if desired.

The proper beat and time elements per measure can be produced for many tunes, yet use only the 35 one-half and one-quarter notes or circles.

Some tunes require with this type of music the use of more chordbars than others. For example, the well-known Pleyel's German Hymn uses six (6) chordbars for a full accompaniment. I have provided for such instances by the addition of two more chordbars to the four (4) already described, namely:

45 #5—G Bb D and #6—Gb A D

45

The wooden teeth numbered 8 in Figures 2, 3, and 4, are simply glued to the bottom of the chordbars, but each chordbar with its teeth could be 50 made out of one piece of wood or other material.

Another modification is painting the bars different colors. For example, blue, green, yellow, and red, and thus assist one to become adept in playing the pianochord which is primarily an instrument for playing accompaniments to a tune or air known to the operator of the pianochord.

55 A great many further modifications or variations in the mechanical construction of my piano-chord is possible without departing from my invention. Accompaniments to many tunes can be played on only two chordbars of three notes each, and then the pianochord's overall width need be only $1\frac{1}{8}$ inches, and its length $6\frac{1}{2}$ inches. Or if three chordbars are used, its width may be 60 only 2 inches. Accompaniments for some two bar tunes can be played in a still more simple manner by duplicating some of the bars. That is, such a toy pianochord may have 5 chordbars to be 65 used progressively. Extremely simple directions for such a tune might be, strike the first bar twice, the second bar four times, the third bar three times, the fourth bar four times, and the fifth bar once, and repeat.

75

Another modification would be to construct a toy piano the keyboard of which would be supplanted by a pianochord that can be designed to act directly on the sound sources, or attached to 5 or removable from the key board.

Figure 5 discloses a further number of modifications, such as, means for using more bars and thus making a fuller accompaniment possible, yet limiting the total width of the pianochord frame 10 to the length of the black piano keys. Also, if the pianochord is lengthened, it can embrace bass notes as well as treble. To avoid the pianochord becoming cumbersome, the octave lower bass note 15 need not be included. Ten chordbars are shown in Figures 6, 7, and 8. Since each is only $\frac{1}{4}$ inch wide, which is less than the thickness of a fore-finger, I have improvised a striking key 11, somewhat similar to those used on a typewriter for each bar, as shown in Figures 6 and 7, and Figure 20 20 shows their relative longitudinal positions on the chordbars as staggered, so that they do not interfere with each other. The striking teeth are shown as dowel pins $\frac{1}{8}$ inch in diameter.

Figures 5 and 6 show the striking pins of only 25 one chordbar which is marked 10.

Another solution for the narrow bar problem is to attach to the top of each chordbar an additional very short bar, which is (transversely of the pianochord) out of line with those of the 30 other chordbars. In Figures 8 and 9, a portion of the chordbar 10 of Figures 5, 6, and 7, is shown but instead of a key or button like 11 in Figures 5, 6, and 7, it is equipped with the short bar 12, Figures 8 and 9, which can be depressed with 35 either a fore-finger or two fore-fingers or other fingers. When only one finger is used the countersink hole 13 assists.

When the pianochord is of the length shown in Figure 5, I add bass notes and the thus enlarged 40 six (6) chords I have already disclosed are:

E_b G B_b E —Sub Dominant—E_b.
B_b F B_b D —Tonic Seventh—B_b.
F F A C Dominant Seventh—F 7th.
C E G B_b C Super Tonic Seventh—C 7th.
G G B_b D —Relative Minor—G Minor.
D G_b A D —Mediant—D.

I have already successfully used these specific chords by applying them to hundreds of tunes and have also used many other chords that have 50 included the sub-mediant.

I have chosen the average pitch of this instrument to best lend itself to accompany group singing when the "C" on the side of the pianochord is placed over middle "C" of a standard keyboard. A very large number of chords and different chord

combinations are possible, and may be chosen to best serve different compositions that may range from classical to jazz.

Although I refer to the construction of a toy piano, above, I fully realize that the pianochord principle can be incorporated into the special construction and design of all kinds and sizes of pianos, so that pianochord player-pianos can fill a field of usefulness just as various types of player-pianos, like the Ampico, that usually involve music rolls and other apparatus, now do. For example, a piano can be initially equipped also with a row of about a half a dozen conveniently located keys or buttons, each of which when depressed by the hand sounds a useful chord. 10 There are an unlimited number of mechanical variations possible for the connection between these typewriter like buttons and the sound producing wires of the piano or other stringed instrument. It is also obvious that the pianochord 15 shown in Figure 2 could be played by the proper manipulation of four (4) buttons or keys in a row, like the piano keys are in a row instead of pressing on the top of either chordbar marked 1, 2, 3, or 4. 20

It is also evident that with the particular type of mechanical construction I have disclosed herewith, it would be best to press bar marked 1 directly over its middle note, although such mechanical nicety is not an essential. However, if 25 arranged in a row, the first button should depress the bar marked 1, the second, bar marked 3, the third, the bar marked 4, and the fourth, the bar marked 2, and suitable mechanical construction adopted to connect each key to it bar. 30

What I claim as new and desire to secure by Letters Patent of the United States, is:

A keyboard player comprising a rectangular framework, having vertical sides and channel shaped ends, the channels of which are inwardly disposed, a plurality of rectangular chordbars, each having on its bottom side projections corresponding with selected keys of a keyboard, said chordbars being loosely disposed side by side, inside said frame with their sides directly in contact with one another, and their ends in loose contact with the channel shaped ends of said framework, whereby the ends of the chordbars are limited in their vertical movements, and collectively the width of said chordbars being only 40 slightly less than the distance between the sides of said framework, whereby side displacement of aid bars is prevented solely by said bars and the sides of said framework. 45

DANIEL McFARLAN MOORE
